(57) **CLAIM**

The ornamental design for a motor vehicle exterior, as shown and described.

DESCRIPTION

FIG. 1 is a front elevational view of a motor vehicle exterior, showing our new design;
FIG. 2 is a left side elevational view thereof;
FIG. 3 is a top plan view thereof;
FIG. 4 is a top, front and left side perspective view thereof; and,
FIG. 5 is a top, rear, and left side perspective view thereof. The portions of the vehicle shown in a de-emphasized and half-tone form and the broken lines that represent a boundary around what is claimed as the design are all for illustrative and environmental purposes that do not form no part of the claimed design.
